CLAIM

(56) **References Cited**

We claim the ornamental design for a bead locator for
control system in architectural coverings, as shown.

U.S. PATENT DOCUMENTS

DESCRIPTION

4,697,629 A * 10/1987 Anderson 160/177

FIG. 1 is an isometric view looking upwardly toward the
bottom of the bead locator of the present invention.

FIG. 2 is an isometric looking down on the bead locator.

FIG. 3 is a bottom plan view of the bead locator.

FIG. 4 is a front elevation.

FIG. 5 is a top plan view.

FIG. 6 is a left side elevation.

FIG. 7 is a rear elevation; and,

FIG. 8 is a right side elevation.
